UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

CENTRIFUGAL UNLOADER.

Application filed May 2, 1923. Serial No. 636,080.

To all whom it may concern:

Be it known that I, SNOWDEN B. REDFIELD, a citizen of the United States, a resident of Easton, county of Northampton, and State of Pennsylvania, have invented a certain Centrifugal Unloader, of which the following is a specification, accompanied by drawings.

This invention relates to compressor unloaders, but more particularly to an unloader for relieving the fluid compression load during the period of starting. The objects of this invention are to enable a compressor unloader to be controlled by the speed of the driving element of the compressor.

Further objects of the invention will hereinafter appear, and the invention is shown in the accompanying drawings in one of its preferred forms, in which—

Figure 1 is a side elevational view partly in section of a compressor unit with my invention applied thereto,

Figure 2 is a view similar to Figure 1 showing the parts in running position,

Figure 3 is a diagrammatic view, partially in longitudinal section of an unloader with a modified form of my invention applied thereto, and

Figure 4 is an enlarged detail view partially in vertical section of the choking needle valve.

Referring to the drawings, the compressor comprises the cylinder A, in which a piston (not shown) reciprocates. The driving element for the compressor piston comprises the crank shaft B, mounted in the frame B' to which the connecting rod C is attached for moving the cross head D. The fly wheel E is secured in any suitable manner to the crank shaft B.

The unloader F is connected to the discharge line G between the compressor and the usual receiver H. The unloader comprises a valve casing J having a main valve chamber K separated from the outlet L by a partition O on which the main check valve P is adapted to be seated for controlling the discharge from the casing. The check valve P is provided with a spring Q bearing on the valve and held by a cap R, which cap also forms a valve guide. The pressure in the receiver tank H normally holds the main check valve P to its seat, when the compressor is idle.

The wall S of the casing J is provided with a valve seat T on which the relief valve U is adapted to be seated for controlling the communication between the main valve chamber K and an atmospheric relief port V, conveniently located on the side of the extension W of the main casing J, in which the relief valve U operates. The relief valve U is preferably carried by a piston X and has limited longitudinal movement relatively to the piston, being urged outwardly from the piston X by a comparatively heavy coil spring Y, in the valve socket Z, of sufficient strength to resist the full line pressure in the main valve chamber K and prevent the relief valve from opening against the spring due to said pressure, when the valve is held to its seat by the combined spring pressure and fluid pressure behind the piston X. The movement of the relief valve is limited by a pin a passing through the transverse aperture b in the valve, and secured at each end of the valve piston X.

The piston X is of the differential type, provided with an enlarged head c forming a pressure area materially greater than the opposed pressure area on the face of the relief valve U and pressure behind the piston head c will force the relief valve U to its seat T with sufficient force to compress the spring Y and also hold the piston head c firmly against the seat d in the extension W, so that leakage past the piston from behind the piston head is prevented. The relative longitudinal movement provided between the relief valve U and the piston X, enables both the valve and the piston to be tightly seated on their seats T and d respectively.

A projection or stop e on the piston X is adapted to bear upon an adjusting screw f in the cap g, by means of which the initial starting position of the piston X and relief valve U may be adjusted. A by-pass h leads from the main valve chamber K and communicates with a port j opening behind the piston X and is controlled by a set screw k forming a choking needle valve. Adjustment of the needle valve k so that the port j is partially closed, will delay the closing point for the piston X and relief valve U.

Greater closing of the set screw or choking needle valve k delays the loading point, but this choking needle valve should preferably be as nearly closed as will allow the device

to operate for loading. Adjustment of the screw f behind the piston X determines the pressure to which the side discharge to atmosphere through the port or vent V will be built up by the relief valve U by the time the compressor has reached full speed. This adjusting screw f should preferably be set at a point to produce just enough throttling at the relief valve U to move the piston inwardly and close the relief valve U when the choking needle valve k is set well towards its seat in the port j . Throttling, due to the slightly open relief valve U needs not be considerable, but should be at least a pound or two, in order to start building up an initial pressure behind the piston X to begin moving the piston X and relief valve U towards the seat T to close the outlet to atmosphere through the port V .

20 A valve casing o in this instance supported by a column p , is provided with an atmospheric vent q . A plunger valve r is adapted to be moved longitudinally in the bore s of the valve casing o . A coil spring t , the tension of which may be adjusted by the set screw u , bears against one end of the plunger valve r . The bore s of the valve casing o is in communication with the extension W of the main valve casing J , rearwardly of the piston X , by means of a pipe or tube v . It will readily be understood that when the compressor is idle, the space in the rear of the piston X in the extension W of the main valve casing, will be open to atmosphere through the pipe or tube v , the bore s of the valve casing o and the atmospheric vent q . By moving the plunger valve r to the left, as shown in Figure 2, the passage of fluid to atmosphere from behind the piston X will be prevented.

25 A frame w is secured to the crank shaft B of the compressor by any suitable means, as screws w' . A plurality of weighted bell crank levers x are mounted on the frame w . The smaller unweighted ends x' of the levers x are in contact with a collar y , which is adapted to be moved longitudinally on the spindle z . The spindle z in this instance, is threaded into the crank shaft B . The extension y' of the collar y is adapted to bear against one end of the plunger r .

30 Assuming that the compressor is starting, the initial position of the parts will be as shown in Figure 1, and fluid pressure will be forced out to atmosphere through the vent V in the extension W of the main valve casing, and a portion thereof will pass from the main valve chamber K , through the passage h , port j , pipe or tube v , through the bore s of the valve casing O and out through the atmospheric vent q . As soon as sufficient speed has been attained, centrifugal force will cause the weighted bell crank levers x to fly outwardly as shown in Figure 2, and by means of the collar y , and extension y' , the plunger valve r will be forced inwardly compressing the coil spring t and close the passage of fluid from the pipe or tube v into the bore s of the valve casing o . Pressure will then be built up in rear of the piston head c of the piston X , to force it inwardly, thereby seating the relief valve U and preventing fluid from passing out to atmosphere through the vent V . Sufficient pressure will then be built up in the valve chamber K to overcome the receiver pressure and unseat the valve P in order to force the fluid pressure into the receiver H .

35 As the compressor stops, the above described operation will be reversed. The weighted levers x will tend to assume their normal or inward position, and thereby permit the coil spring t to move the plunger valve r to the right, and open the passage of fluid from the extension W of the main valve casing in rear of the piston X to atmosphere through the port q in the valve casing o . Pressure fluid will be allowed to pass out of the tube v and vent q faster than it can enter the space back of the piston head c through choking needle valve k . This will reduce the fluid pressure back of the piston head c to such a point that the pressure in the main chamber K will unseat the relief valve U , thereby allowing fluid to pass out through the atmospheric vent V . Load will thus be thrown off the compressor and enable the compressor piston to re-start unloaded.

40 In the modification shown in Figures 3 and 4, the same principle heretofore described is applied to an unloader in which the passage h in the extension W of the main valve casing is omitted. In this instance, the pipe or tube 2 is connected to the main valve chamber K' and is in communication with the valve casing o' , which is supported in any suitable manner, as by the angle bar p' . The bore s' in the valve casing o' communicates with the smaller bore t' which is in communication with the pipe or tube v' . The opposite end of the pipe or tube v' is connected to the extension W' of the main valve casing rearwardly of the piston X' . A ball check valve u^2 urged against its seat h' by the coil spring u' controls the passage of pressure fluid from the main valve chamber K' to the rear of the piston X' . A ball check valve x' in the bore y^2 of the valve casing o' is spaced from the ball valve u^2 by the spacer pin z' and controls the atmospheric vent 3 .

45 A plate 4 secured in any suitable manner to the end of the compressor shaft 5 as by means of the screws 6 , is provided with the lugs 7 . The weighted bell crank levers 8 are pivotally mounted on the lugs 7 , and are adapted to bear against the head 9 of the plunger 10 for moving the plunger inwardly, in the casing o' . The inner end 11

of the plunger 10 is adapted to bear against and seat the ball valve α' . A coil spring 12 is secured at its ends to the pins 13 in the levers 8, and serves to hold the levers 8 normally in their inward position. If desired, two coil springs may be used, one on each side of the weighted levers 8.

Assuming that the compressor is starting, the weighted levers will be caused to move outwardly by centrifugal force, and thereby move the plunger 10 inwardly to seat the ball valve α' . By means of the spacer α' , the ball valve α will be unseated thereby permitting fluid pressure to flow from the main valve chamber K' through the pipe or tube 2 into the bore s' of the valve casing α' , through the bore t' , and thence through the pipe or tube v' to the rear of the piston X' . The piston X' will thereupon be forced inwardly, and the relief valve U' will be forced to its seat T' , thereby closing the atmospheric vent V' in the extension W' of the main valve casing.

On stopping, the levers 8 will tend to move together by the action of the coil spring 12, thereby permitting the coil spring α' to seat the ball valve α^2 and by means of the spacer pin α' , unseat the ball valve α' . Pressure fluid may then pass from behind the piston X' through the pipe or tube v' into the bore t' of the valve casing α' and thence to atmosphere through the vent 3.

As shown in Figure 4, I provide a set screw 14 preferably threaded into the main valve chamber K' forming a choking needle valve, which controls the amount of fluid passing out of the main valve chamber K' into the pipe or tube 2. By regulating the choking needle valve, the closing point of the relief valve U' may be delayed or hastened as desired.

I claim:

1. A centrifugal compressor unloader comprising a relief valve in the discharge line exposed on both ends to pressure directly from the compressor and controlling a vent to atmosphere, a centrifugally operable pilot valve, and a conduit connecting one face of the relief valve through the pilot valve with atmosphere, said pilot valve being adapted to control the opening of said

conduit to atmosphere whereby the relief valve is arranged to be actuated.

2. A centrifugal compressor unloader comprising a relief valve in the discharge line exposed on both ends to pressure directly from the compressor and controlling a vent to atmosphere, a centrifugally operable pilot valve, and a conduit connecting one face of the relief valve through the pilot valve with atmosphere, and adjustable means restricting the flow of air to and from one side of the relief valve.

3. A centrifugal compressor unloader, comprising an unloader mechanism adapted to be connected in the discharge line of the compressor, said unloader mechanism comprising a main discharge valve casing, provided with a discharge valve chamber, a main discharge valve controlling the outlet from the casing, an extension connected to said casing, a piston in the extension, a relief valve having limited movement in the piston, adapted to control an atmospheric vent in the extension, a connection between the discharge valve chamber and the space in rear of the piston, a choking valve controlling the flow of fluid through said connection, centrifugal means for controlling the operation of the unloader mechanism operatively connected to the driving element of the compressor comprising a frame, a plurality of weighted bell crank levers pivotally mounted on the frame, a spindle secured to the frame, a collar provided with an extension slidably mounted on the spindle, the movement of the collar on the spindle being controlled by one end of the bell crank levers, a plunger valve casing in communication with the extension of the main valve casing rearwardly of the piston, a plunger valve in the plunger valve casing adapted to be moved in one direction by said extension for controlling an atmospheric vent therein, a spring in the plunger valve casing opposing the movement of the valve in one direction, whereby the load is thrown on and off the compressor in accordance with its speed.

In testimony whereof I have signed this specification.

SNOWDEN B. REDFIELD.
